UNITED STATES PATENT OFFICE.

RUSSELL B. KINGMAN, OF ORANGE, NEW JERSEY, ASSIGNOR TO METAL TEXTILE CORPORATION, OF WEST ORANGE, NEW JERSEY, A CORPORATION OF RHODE ISLAND.

ABRASIVE FABRIC.

Original application filed May 16, 1924, Serial No. 713,724. Divided and this application filed May 2, 1925. Serial No. 27,410.

To all whom it may concern:

Be it known that I, RUSSELL B. KINGMAN, a citizen of the United States, residing at Orange, in the county of Essex and State of

- 5 New Jersey, have invented certain new and useful Improvements in Abrasive Fabrics; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.
- 15 This invention relates, generally, to improvements in abrasive fabrics; and more particularly to shrinkless abrasive fabrics as set forth in my co-pending application for Letters Patent Ser. No. 713,724, filed May 20 16th, 1924, and of which the present application is a division.

The present invention has for its principal object to provide an abrasive fabric consisting of metal gimped weft threads or strands 25 with which are interconnected or knit both vegetable yarn and metallic cross threads so related to one another that not only is a highly efficient abrasive quality imparted to the fabric, but the finished fabric is adequately braced against shrinking, and consequently cloths and other scouring articles 30 made therefrom definitely and positively retain their shape, and therefore always present in use a desired comparatively flat 35 abrasive surface. Furthermore, in the novel fabric, possessing the said shrinkless character, the meshes thereof remain open, so that thorough cleansing of the cloth after use is easily accomplished, whereby the same 40 may be easily kept in a clean, sweet and sanitary condition, free from accumulations of dirt and grease.

With the above objects of the present invention in view, the same consists in a fabric 45 comprised of suitable spaced weft threads or strands of suitable material, such as vegetable yarn, jute or like base material, which are gimped with one or more metallic threads or strands by spirally winding, 50 twisting or convoluting the latter about the former from end to end. It is preferable that the metal gimping should be done with thin ribbon-like or flat wire made of a non-

corrosive metal possessing a suitable degree of hardness, such, for example, as copper. 55 The metal gimped weft threads are interconnected and held together, in suitably spaced relation one to another, by vegetable yarn cross threads or strands, which are preferably interlooped or knit by a lock or 60 chain stitch transversely across the spaced gimped weft threads, and alternated with said vegetable yarn cross threads or strands are metallic cross threads or strands in separate parallel spaced relation thereto, said 65 metallic cross threads being also preferably interlooped or knit with the gimped weft threads by a lock or chain stitch. By the described alternated parallel relation of said vegetable yarn and metallic cross or weft 70 threads, the vegetable yarn cross threads provide a desired degree of water absorptive material in addition to the body of the weft threads, while the metallic cross threads provide abrasive elements in addition to that 75 provided by the gimping of the weft threads, while at the same time serving to firmly brace the finished fabric against contraction or shrinkage. Said metallic cross threads may be of any desired cross-section 80 shape.

This invention is clearly illustrated in the accompanying drawings, in which:—

Figure 1 is a face view of a square of the novel abrasive fabric made according to 85 the principles of this invention; and Figure 2 is an enlarged fragmentary detail face view of the same.

In producing the novel shrinkless abrasive fabric embodying the principles of this 90 invention, I take a base thread 3 of any suitable material, preferably made, however, of a vegetable fiber such as jute, and I twist or turn around the body thereof one or more metallic strands 4, thereby gimping such 95 base thread 3 with metal, so that abrasive elements are provided by the convolutions of such metallic material. I prefer to use a form of metallic strand which will, when thus convoluted or gimped on the base thread, provide a multiplicity of sharp edges or projections, so that a maximum of abrasive efficiency is attained, and, therefore, I select for the purpose a thin ribbon-like or flat copper wire, although I do not intend 100 to limit myself necessarily to wire of such 105

conformation, but may use a wire of any other cross-sectional shape. Having provided the metallic wire gimped base thread, by suitable machinery the same is laid to 5 form the weft of the fabric. The gimped weft threads are then interconnected by cross threads or strands. In making up abrasive fabrics suitable for scouring and similar purposes, it is desirable to produce 10 a comparatively coarse or open mesh by holding the gimped weft threads spaced apart one from another. In order to provide for such comparatively wide spacing of the weft threads in the finished fabric, I 15 knit the cross threads to form interlocked loops or links, which surround and hold the weft threads both strongly interconnected as well as spaced apart at the proper distance, according to the size of mesh desired. In 20 the instant species of my invention I employ cross threads of two different materials, to wit, cross threads 5 of vegetable yarn, such, for example, as cotton, and cross threads 6 of metallic wire, such as copper. 25 The yarn cross threads 5 and metallic cross threads 6 are disposed in alternated parallel relation, at desired spaced intervals throughout the total area of the fabric. By such arrangement a metallic thread 6 will 30 be disposed adjacent to a yarn thread 5, and thus the yarn threads will be braced against contraction when the fabric is wet, because of the resistance of the metallic threads 6 to such contraction, and consequently the entire fabric is rendered substantially shrink- 35 less. At the same time the metallic threads 6 serve to provide additional abrasive ac-

tion, since the same provide additional metallic projections distributed transversely throughout the area of the fabric. From the 40 above it will be understood, that the fabric so constructed will easily retain the desired flat open mesh condition and shape, whereby not only is its abrasive efficiency increased, but it is also the more readily subjected to 45 thorough cleansing and rinsing to free the same from the dirt and grease accumulated thereon when in use, and consequently may be easily kept in a clean, sweet and sanitary condition. 50

I claim:—

1. An abrasive fabric comprising weft threads gimped with metallic wire, yarn threads interconnected to and across said weft threads to produce an open mesh, and all-metal threads also interconnected across said weft threads in separated and alternated parallel relation to said yarn threads at desired intervals relative to the length of said gimped weft threads. 55

2. An abrasive fabric comprising jute weft threads gimped with flat metallic wire, vegetable yarn threads knitted across said weft threads to space the same apart to produce an open mesh, and additional threads of metallic wire also knitted across said weft threads in separated and alternated spaced parallel relation to said yarn threads throughout the area of the fabric. 65

In testimony that I claim the invention set forth above I have hereunto set my hand this 30th day of April, 1925. 70

RUSSELL B. KINGMAN.
